UNITED STATES PATENT OFFICE.

JOSEPH C. BARNHART, OF MARION, INDIANA.

RESERVE-FUEL-SUPPLY TANK.

Application filed April 17, 1922. Serial No. 553,327.

To all whom it may concern:

Be it known that I, JOSEPH C. BARNHART, a citizen of the United States, residing at Marion, in the county of Grant and State of Indiana, have invented certain new and useful Improvements in Reserve-Fuel-Supply Tanks, of which the following is a specification.

The present invention relates to an auxiliary fuel supply tank which is adapted to be associated with the main fuel supply tank of a motor vehicle, for the purpose of carrying an emergency supply of fuel which can be used in the event the main supply of fuel becomes exhausted. The reserve fuel supply tank will hold a sufficient amount of fuel to drive the motor vehicle several miles. The driver of the vehicle thus always has an emergency supply of fuel held in reserve and sufficient in quantity to carry him to a fuel supply station if he unexpectedly discovers that his main supply of fuel has become exhausted when he is at a distance from home or from a fuel supply station.

Among the objects of the invention are to provide a reserve fuel supply tank which embodies novel features of construction, whereby it is associated with the main fuel supply tank in such a manner that there will be little or no danger of the driver of the vehicle failing or forgetting to refill the energy reserve fuel supply tank after he has had occasion to use the same. The invention also contemplates the provision of an emergency fuel supply tank of this character which provides for easily and quickly transferring the emergency supply of fuel from the reserve fuel tank into the main fuel tank, and which may also be graduated and formed so that it can be utilized as a measuring stick or gauge for determining the quantity of fuel in the main tank.

With the above and other objects in view, the invention consists in certain combinations and associations of the parts as will be more fully described as the description proceeds; the novel features thereof being pointed out in the appended claims.

For a full understanding of the invention reference is to be had to the following description and accompanying drawings, in which:

Figure 1 is a side elevation of a reserve fuel supply tank, which is constructed in accordance with the invention, the said re-

serve fuel supply tank being shown as positioned within the main fuel supply tank, of which a fragmentary portion is shown, and portions being broken away and shown in section to illustrate more clearly the details of construction.

Figure 2 is an enlarged sectional view through the lower end of the reserve fuel supply tank, illustrating in detail the valve controlled outlet.

Figure 3 is a top plan view of the reserve fuel supply tank.

Figure 4 is a horizontal sectional view on the line 5—5 of Figure 1.

Figure 5 is an enlarged sectional view on the line 6—6 of Figure 2.

Figure 6 is a view similar to Figure 1, showing a slightly modified form of the invention, in which the valve controlled outlet opening at the bottom of the reserve fuel supply tank is omitted.

Corresponding and like parts are referred to in the following description and indicated on all of the views of the drawings by like reference characters.

Referring to Figures 1 to 5 inclusive of the drawings, which illustrate one of many possible embodiments of the invention, the reference numeral 1 designates the body portion of the reserve fuel supply tank, and this is normally positioned within the interior of the main fuel supply tank A of the motor vehicle upon which the equipment is mounted. The reserve tank 1 is of an elongated form and is of such a size and shape transversely that it can be readily passed through the filling opening 2 of the main tank. This filling opening is surrounded in the usual manner by an internally threaded fitting 3, which is adapted to be engaged by an externally threaded cap 4, said cap being removed when it is desired to fill the main supply tank, and being thereafter replaced to prevent the contents of the main supply tank from splashing out or being spilled from the opening.

In the present instance the cap 4 is of a special formation, being provided with a depending lip 5 which has a threaded engagement, as indicated at 6, with the upper end of the reserve fuel supply tank 1. The reserve tank 1 is thus rigidly applied to the cap 4 and carried thereby, being lifted out of the main supply tank A when the cap is unscrewed and removed from position, and being inserted within the main sup-

ply tank when the cap is applied to the filling opening and screwed upon the fitting 3. The top of the cap may, as indicated by Figure 3, be provided with a 5 transversely extending web 7 which projects upwardly and provides a finger piece, thereby enabling a firm grip to be obtained upon the cap for the purpose of screwing the same into position or unscrewing it 10 therefrom. The cap has one air inlet opening 8 which communicates with the interior of the reserve fuel supply tank 1, and a second air inlet opening 9 which is arranged in an angular position and opens into the 15 main supply tank A. These are the usual air inlet openings, which provide for the necessary ingress of air into the respective tanks when the liquid contents thereof are withdrawn from the tanks.

20 It is contemplated that the reserve fuel supply tank may be used in the capacity of a gauge or measuring stick, for the purpose of determining the quantity of liquid fuel which is in the main supply tank A. For 25 this purpose the exterior of the reserve tank 1 is shown as provided with a series of graduations 10, which are arranged at the proper intervals of space and associated with proper legends to indicate the quantity of 30 gasoline in the tank. In this connection it is perhaps unnecessary to explain that the reserve fuel supply tank is used in the same manner as the ordinary measuring stick. When the small elongated tank 1 is with- 35 drawn from the main tank A, the portion thereof which was submerged in the liquid fuel within the main tank will be moistened with the fuel, and the relation between the moistened exterior portion of the reserve fuel tank and the graduations 10 on the tank will indicate the quantity of liquid fuel 40 within the main tank. It may also be noted that a certain zone of the elongated reserve fuel supply tank has the exterior thereof 45 roughened or knurled, as indicated at 11, so that a firm grip can be obtained upon this reserve fuel supply tank when applying it to the cap 4 or disengaging it therefrom.

50 The bottom of the reserve fuel supply tank 1 is provided with an opening within which the upper end of a hollow casing is fitted, said casing being formed of an upper complemental section 12^a, and a lower complemental section 12^b. These complemental casing sections are flanged at 55 their meeting edges, as indicated at 12^c, and a transverse partition 13 extends transversely across the interior of the hollow casing, the periphery of the partition being received between the flanges 12^c. Fastening 60 members such as the rivets 14, extend through the flanges 12^c, the partition 13, and the bottom of the reserve supply tank 1, thereby performing the triple function 65 of fastening the hollow casing to the

tank, securing the two sections of the hollow casing together, and holding the transverse partition in opposition. Both of the sections of the hollow casing are provided with comparatively large openings 15, and the partition 13 is formed with an opening surrounded with a valve seat 16. A downwardly opening ball valve 17 normally engages the valve seat, being yieldably urged into a closed position by a coil spring 70 18. The ball valve operates within a cage or guide 19, the lower end of the cage being formed with a neck which receives the spring 18 and holds the spring in position. This ball valve 17 normally closes the 75 bottom of the reserve fuel supply tank and holds the contents thereof separate from the contents of the main fuel supply tank, although it will be obvious that after the main tank has been emptied the contents of the 80 reserve tank can be transferred or drained into the main tank by opening the valve 17.

Extending longitudinally through the reserve fuel supply tank 1 is a plunger 20, the 85 upper end of the plunger extending slidably through an opening in the cap 4, while the lower end thereof extends through a neck 21, provided at the top of the casing section 12^a. The lower extremity of the plunger terminates slightly above the normal or seated 90 position of the ball valve 17, so that when the plunger is pushed downwardly the ball valve will be moved away from its seat. An intermediate portion of the plunger 20 extends loosely through a guide ring 22, which is carried by a frame or cage member 23 pendant from the cap 4. The upper end of a coil spring 24 which surrounds the plunger 20 bears against the guide ring 22, while the lower end of the coil spring engages a set collar 25 which is fixedly mounted upon the plunger. This spring is normally under compression and is stronger than the 95 before mentioned valve spring 18, so that when the plunger is released the action of this spring will force the plunger downwardly and cause the ball valve 17 to be moved against the action of the spring 18, 100 so that when the plunger is released the action of this spring will force the plunger downwardly and cause the ball valve 17 to be moved against the action of the spring 18 into an open position. The upper end of 105 the plunger 20 is provided with a laterally projecting finger piece or arm 26 which is adapted to engage a cam 27 formed in connection with the top of the cap 4. When 110 this arm 26 is rotated and brought into engagement with a notched seat 28 at the raised portion of the cam, the plunger is moved upwardly against the action of the spring 24 and held in an inoperative position. The ball valve 17 is then retained in 115 a closed position by the action of the spring 18. Under these conditions the reserve supply of fuel which is held in the tank 1 is maintained separate from the fuel in the 120 main supply tank A. However, if the main 125 supply tank A is emptied, the ball valve 17 is 130 retained in an open position by the action of the spring 18, so that the fuel in the main supply tank A can be transferred into the reserve fuel supply tank 1.

supply of fuel becomes unexpectedly exhausted when the driver of the vehicle is away from home or at a distance from a fuel supply station, it is merely necessary to grasp the arm or finger piece 26 at the upper end of the plunger 20 and rotate the arm toward the lower end of the cam 27. This permits the plunger to be moved downwardly by the action of the spring 24 with the result that the lower end of the plunger forces the ball valve 17 downwardly against the action of the spring 18 and unseats the valve. The reserve supply of fuel can then pass through the opening in the bottom of the reserve tank 1 into the main tank A, from whence it is fed to the engine in the usual manner, and the reserve supply of fuel is sufficient to drive the vehicle for several miles, so that the driver can obtain a fresh supply of fuel before the fuel in his two tanks becomes completely exhausted. As has been previously mentioned, the reserve fuel supply tank 1 is carried by the cap 4 for the filling opening of the main tank, so that there is little probability of the driver forgetting to refill the reserve tank when the main supply tank is filled.

A slight modification is shown by Figure 6 in which the outlet valve and the valve controlling means are omitted from the reserve fuel supply tank. In all other respects the construction and manner of operation of the fuel supply tank shown by Figure 6 is identical with that previously described. The same reference numerals have accordingly been applied to this figure and it is not believed that any further description is necessary. The construction can be somewhat simplified and the cost of producing the device decreased by leaving off the valve mechanism, and when it becomes necessary to transfer the reserve supply of fuel into the main tank the reserve tank is withdrawn from the main tank, unscrewed from the cap, and the fuel therein poured into the main tank.

Having thus described my invention what I claim as new and desire to secure by Letters Patent is,

1. The combination with a main fuel supply tank with its filling opening and cap, of a reserve fuel supply tank carried by the cap and normally projecting into the main tank, said reserve tank being graduated upon its exterior so that it can be used as a gauge stick to determine the quantity of fuel in the main tank.

2. The combination with a main fuel supply tank with its filling opening and cap, of an elongated reserve fuel supply tank carried by the cap and insertable through the filling opening of the main tank, so as to normally project into the contents of the main tank, the exterior of the reserve tank being graduated so that it can be used as a

gauge stick to determine the quantity of fuel in the main tank.

3. The combination with a main fuel supply tank with its filling opening and cap, of a reserve fuel supply tank carried by the cap and having a detachable connection therewith, said reserve fuel supply tank being insertable through the filling opening of the main tank, and the cap being provided with separate air inlet ports leading to the main tank and reserve tank respectively.

4. The combination with a main fuel supply tank, having a filling opening, a removable cap therefor having an interlocking connection, of a reserve fuel supply tank closed at its upper portion and attached to the cap for bodily insertion and removal through the filling opening of the main tank, a valve controlled outlet for the reserve tank, and means independent of the valve and operable from the top of the cap for controlling said outlet.

5. The combination with a main fuel supply tank having a filling opening and cap, of a reserve fuel supply tank carried by the cap, an outlet valve in the bottom of the reserve tank having automatic closing means, a plunger carried by the cap and extending through the reserve tank for unseating said valve, a guide member supported by the cap and engaging an intermediate portion of the plunger, yielding means acting upon the plunger and normally tending to overcome the tension of the valve closing means, and means actuated by rotation of the plunger for moving the same to tension said yielding means and hold the plunger in inoperative position.

6. The combination of a main fuel supply tank, a reserve fuel supply tank associated therewith, a casing applied to the reserve tank and formed with an outlet opening, a spring seated valve mounted within the casing and normally closing the outlet opening, a spring actuated plunger extending through the casing and reserve tank and tensioned to engage the valve to open the same, and means for normally holding the plunger in an inoperative position.

7. A reserve fuel supply tank having a cap at the top thereof, and an opening in the bottom thereof, a perforated casing fitted within the opening and formed with a transverse partition having an outlet opening therein, a spring seated valve mounted within the casing and normally closing the outlet opening, a spring acting plunger extending through and guided by the casing and cap and tensioned to unseat the valve, a lateral arm upon the plunger, and a cam arranged upon the cap for cooperation with the lateral arm to hold the plunger normally in an inoperative position.

In testimony whereof I affix my signature.
JOSEPH C. BARNHART.
